UNITED STATES PATENT OFFICE.

ODILON GRISÉ, OF SPRINGFIELD, MASSACHUSETTS.

THILL-COUPING.

SPECIFICATION forming part of Letters Patent No. 228,993, dated June 22, 1880.

Application filed February 16, 1880.

To all whom it may concern:

Be it known that I, ODILON GRISÉ, of Springfield, county of Hampden, and State of Massachusetts, have invented new and useful 5 Improvements in Thill-Couplings, which improvements are fully set forth in the annexed specification and in the accompanying drawings.

My invention relates to thill-couplings which 10 are constructed with a view to prevent their rattling; and it consists in adapting to an axle-clip of ordinary construction a thill iron or coupling constructed with a wide oblong bolt-hole transversely through it, providing therein 15 in sufficient room for said bolt for a surrounding elastic packing for it and for a pressure-block, and having a set screw or screw-bolt operating through one end of said oblong bolt-hole at right angles to said bolt against said 20 pressure-block, to cause the bolt to be tightly secured between said elastic packing and within said wide oblong bolt-hole.

In the drawings, which consist of three figures, Figure 1 is a sectional view through the 25 line x x , Fig. 2. Fig. 2 is a side elevation, partly in section, showing one thill-iron support removed. Fig. 3 is the bolt which connects the thill-iron to the axle-clip.

A is the thill-iron provided with the oblong 30 bolt-hole b . C is the axle-clip, and e e are the thill-iron supports thereon. i is a screw-bolt. o is a pressure-block. s s are sections of elastic packing, and t is the connecting-bolt.

I construct the thill-iron A with the oblong 35 bolt-hole b , as shown, and fit the screw-bolt i through one end of said bolt-hole, and fit into the latter under the end of bolt i the pressure-block o . Between the under concave edge of block o and the lower end of the oblong bolt-hole b the bolt t passes transversely through;

but space is provided between the latter-named parts and the sides of bolt t for the interposition between them of the elastic packing s s , lying around said bolt and extending over that portion of it which is within the bolt-hole b . 45

The axle-clip C is constructed of the usual form and is provided with the thill-iron supports e e , pierced for bolt t , which is secured therein by a nut in the usual manner. 50

Thus when the above-named parts are placed, as shown, in the bolt-hole b , and bolt t is inserted through supports e e and through the bolt-hole between the elastic pieces s s , said bolt will not come in contact with any part of 55 the thill-iron A , and by screwing bolt i down against block o bolt s becomes tightly compressed between the sides of said elastic packing, and all rattling of parts is prevented.

My improved thill-iron possesses advantages 60 over other thill-irons in which elastic packing is interposed between the outer end of the thill-iron and the axle-clip in that the elastic packing is so protected by being inclosed within the bolt-hole and between the sides of supports e e that it is much more durable and all wear thereof can be taken up by screwing down bolt i . 65

What I claim as my invention is—

The combination, with the axle-clip C , provided with the supports e e and with bolt t , of the thill-iron A , provided with the oblong bolt-hole b and the screw-bolt i , the pressure-block o , and the elastic packing s s , substantially as and for the purpose set forth. 70

ODILON GRISÉ.
